TELEPHONE TRANSMITTER MOUNTING

Filed Sept. 28, 1922

Inventor:
George R. Lum
by *Jed C.R. Palmer ATTY.*

UNITED STATES PATENT OFFICE.

GEORGE R. LUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE TRANSMITTER MOUNTING.

Application filed September 28, 1922. Serial No. 591,016.

This invention relates to transmitter stands and particularly to portable type stands in which the transmitter is enclosed.

The object of the invention is to provide a portable transmitter stand of simple construction, which will afford a transmitter maximum protection against major shocks and practically insulate it against minor vibrations and at the same time be free from acoustical effects which would distort the sound waves.

In accordance with the general features of the invention a transmitter stand is provided with an enclosure in the center of which the transmitter may be resiliently supported, the enclosure having non-resonant and non-reflecting walls for affording protection to the transmitter without interfering with the transmission of the sound waves. In its preferred embodiment, the invention provides a drum-shaped cage of foraminated material such as metal screen reenforced by slightly heavier perforated walls to give it sufficient rigidity, the cage being mounted upright on a suitable base, and provided with resilient means such as springs for supporting the transmitter centrally within the enclosure.

Referring to the drawings:

Fig. 1 is a front view with a section of the face removed.

Fig. 2 is a side view having a section removed showing the means for holding the cover on the stand.

On a base 2 is vertically mounted a perforated band 3, preferably of a cylindrical shape, the inner periphery of which is lined with a fine mesh screen 4 extending over the perforations 5. One end of the band 3 is closed by a foraminated wall 6 and the other end is closed by a like wall 7. The walls 6 and 7 are preferably perforated frames or plates, lined with screens 8 and 9, which cover the perforations therein. One face is removable so as to provide access to the interior of the stand. For this purpose snap clips 10 are provided on the face 9, which engage corresponding springs 12 on the band 3. A notch 11 provided on the edge of face 7, engages a pin 16 in the base 2 in order to facilitate replacing the face. Within the frame 3 and spaced equidistant, are eyes 13. Transmitter 14, which is preferably of the type described in application Serial No. 570,970, filed June 26, 1922, is provided with

a corresponding number of eyes 17 about its periphery. Springs 15 support the transmitter and protect it against minor as well as major shocks.

The invention claimed is:

1. A transmitter mounting comprising an enclosure having a perforated band of cylindrical form, a perforated closure for each end of said band, a fine mesh screen completely lining said band and said closures and shock-absorbing means supporting said transmitter within said enclosure and out of contact therewith.

2. A portable telephone stand comprising a base, a perforated cylindrical band supported vertically, with its axis horizontal on said base, perforated coverings for each end of said band, one of said coverings being readily detachable, and means attached to said band for supporting a transmitter against shocks and out of contact with said band and said coverings.

3. A telephone stand comprising a base, a cylindrical band of thin metallic material having large perforations therein, supported vertically with its axis horizontal to said base, perforated truncated cone-shaped front and rear covers for said cylindrical band, a metallic lining for said band and said covers, covering all openings therein and forming with said band and covers a non-resonant and non-sound reflecting chamber, and means attached to said band for supporting a transmitter against shocks and out of contact with said band and said coverings.

4. A portable telephone stand comprising a substantially cylindrical enclosure, having a perforated cylindrical wall, and conical-shaped front and rear walls, one of said walls having a relatively large central opening and a plurality of equally spaced marginal openings, a metal gauze lining for all of said walls and covering the perforated openings therein, and a base for supporting said enclosure.

5. A transmitter mounting comprising a substantially cylindrical enclosure having a perforated cylindrical wall, rear and front walls having central and marginal perforations therein, a central perforation being substantially the diameter of said transmitter, resilient means supporting said transmitter against external shocks, and coaxial with said central perforations, gauze cover-

ing the perforations in all walls, and a base supporting said cylindrical enclosure with its axis horizontally disposed.

6. A transmitter mounting comprising a drum-shaped cage of metal gauze, means for reinforcing said cage comprising a thin metallic frame having perforations therein, a base supporting said cage in an upright

position, and shock absorbing springs attached to said frame for supporting a transmitter in spaced relation with the walls of said cage. ¹⁰

In witness whereof, I hereunto subscribe my name this 26th day of September, A. D., 1922.

GEORGE R. LUM.
